UNITED STATES PATENT OFFICE.

CHARLES F. BIRTMAN, OF CHICAGO, ILLINOIS.

OZONE-GENERATOR.

No. 811,364.

Specification of Letters Patent.

Patented Jan. 30, 1906.

Application filed June 9, 1905. Serial No. 264,489.

To all whom it may concern:

Be it known that I, CHARLES F. BIRTMAN, a citizen of the United States, residing at Chicago, in the county of Cook and State of Illinois, have invented certain Improvements in Apparatus for Generating Ozone, of which the following is a specification.

This invention relates to certain improvements in apparatus for generating ozone, and more particularly in that class of such apparatus wherein the generation is effected by the formation of an electric discharge across an air chamber or passage; and the object of the invention is to provide an apparatus of this general character of a simple and inexpensive nature by means of which the ozone may be generated in considerable volume and wherein means are provided for regulating such generation and also for regulating the supply of the generated ozone to a patient where the apparatus is designed for electrotherapeutic employment.

The invention consists in certain novel features of the construction, combination, and arrangement of the several parts of the improved ozone-generating apparatus whereby certain important advantages are attained and the device is rendered simpler, cheaper, and otherwise better adapted and more convenient for use, all as will be hereinafter fully set forth.

The novel features of the invention will be carefully defined in the claims.

In the accompanying drawings, which serve to illustrate my invention, Figure 1 is a broken plan view of an apparatus embodying my invention, and Fig. 2 is a partial end elevation showing the means for supplying the generated ozone to patients when the apparatus is employed for electrotherapeutic treatment. Fig. 3 is a sectional view drawn to a larger scale and taken horizontally through the generating-chamber of the apparatus. Fig. 4 is a vertical section taken longitudinally through the generating-chamber of the apparatus in the plane indicated by the line *a—a* in Fig. 3. Fig. 5 is a detached perspective view showing one of the notched strips for supporting the electrodes within the generating-chamber of the apparatus. Fig. 6 is an end view of the improved generating apparatus, illustrating the arrangement of the blower or air-forcing device, together with various circuit connections to be hereinafter referred to. Fig. 7 is an enlarged sectional detail view showing the construction

of the swivel-support for the mouthpiece and discharge-tube of the apparatus. Fig. 8 is a diagrammatic view showing the circuit connections of the improved apparatus when designed for use with a static electrical machine as a source of supply. Fig. 9 is a view similar to Fig. 8, but showing the circuit connections of the apparatus when designed for employment with an alternating-current generator as a source of supply.

As shown in the views, the improved apparatus comprises a base or support, which may be of any desired construction, but which is preferably provided with a flat upper surface or table 1, upon which is centrally arranged the generating-chamber, which is indicated as a whole at 2 and comprises lower and upper parts 3 and 4, of non-conducting material of rectangular form, and between which at the angles of the rectangular casing or chamber are extended posts or uprights 5 5, the sides and ends of said casing or chamber 2 being closed by plates 6 6, of glass or other suitable material, the edge portions of which are let into the posts or uprights 5 5 and into the top and bottom plates 4 and 3, as indicated in Figs. 3 and 4.

Within the chamber or casing 2 thus formed is provided an interior or auxiliary casing, also of rectangular construction and formed of corner posts or uprights 9 9, extended from the bottom plate 3 to the top plate 4 of the casing 2, the sides of said interior casing being closed by means of sheets or plates 7 7, of non-conducting material, held in place in a way similar to the glass plates 6 above referred to. The ends of the interior casing are similarly closed by end plates 8 8, also of non-conducting material, the arrangement being such that a generating chamber or compartment 10 is produced within the interior casing, the walls of which generating chamber or compartment are formed wholly of non-conducting material.

The dimensions of the interior casing are such that a space is produced within the casing 2 and surrounding said interior casing, as clearly shown in Figs. 3 and 4, and for the supply of air to said generating chamber or compartment 10 within the interior casing I provide an air-supply pipe or conduit 11, also formed, by preference, from non-conductive and non-corrosive substance, which is extended across the space intervening between the end walls of the inner and outer casings and has an end portion communicating with the

- chamber or compartment 10 by way of a central opening produced in the end wall 8 of the interior casing, the opposite end of said pipe or conduit 11 being extended through an opening in the end plate 6 of the outer casing and being bent down outside the casing 2, as indicated at 14, and passed through the flat top plate or table 1 of the supporting-base, beneath or within which said downwardly-extended portion 14 of the air-supply pipe or conduit has connection with a blower or air-forcing device 15 of any preferred kind, for the operation of which an electric motor 16 may be conveniently employed.
- 15 16^b 16^b indicate the circuit wires or conductors for the supply of said motor 16, and 16^a indicates a switch or controller of any preferred kind, included in the motor-circuit and preferably located upon the support or base of the apparatus in convenient position for use by the operator for controlling the motor, and thereby controlling the supply of air from the blower 15 through pipes 14 and 13 to the generating-chamber 10 of the apparatus, so that the proportions of pure and ozonized air supplied to a patient by way of the discharge devices (to be hereinafter described) may be controlled and varied at will.
- The end walls or plates 8 of the interior casing of the apparatus are provided with vertical grooves or channels 20, parallel with each other, but spaced apart and designed to receive and hold the end edge portions of glass partitions or plates 21 21, which are extended vertically within the generating chamber or compartment 10 from end to end thereof, as clearly seen in Figs. 3 and 4, the construction and arrangement of these plates or partitions being such that passages 22 22 are produced between them and extended lengthwise and vertically in the chamber 10, said passages 22 22 being in communication with each other through openings 23 23 at opposite ends of the chamber and produced by notching or cutting out the central portions of the end edges of the glass plates or partitions 21 21, so as to afford free circulation of air between the passages 22 22 at the end of the interior casing, whereat the air-supply pipe or conduit 11 is located, and also at the opposite end of said interior casing, whereat is located a discharge pipe or conduit 12 similar to the pipe or conduit 11 and similarly extended across the space between the inner and outer casings and passed through an opening in the plate 6 at that end of said outer casing.
- In the spaces or passages 22 22 intervening the glass partitions or plates 21 21 in the generating-chamber 10 are located other glass plates or non-conducting supports 24 24 of less lengths than said plates or partitions 21 21, the plates or supports 24 being held in positions central between the partitions 21 21, between which they are

ranged by means of grooved strips 30 30, rested on or secured to the bottom plate 3 of the casing 2 and upper strips 27, which are rested upon the upper edges of partitions 21 21 beyond the ends of the supporting-plates 24.

The upper and lower edges of the plates 21 and 24 are centrally cut away or notched out, as seen at 31 in Fig. 4, and the lower retaining-strips 30 are transversely extended upon the bottom plate 3 across the chamber 10 in such a way as to pass through the space produced beneath the plates 21 and 24 by such cutting away of their central lower edge portions, said retaining-strips being, however, provided with notches 29, in which the downwardly-extended end portions of the plates 24 are engaged in such a way as to securely position the said plates 24 in the passages 22 between partitions 21. The shorter supporting-plates 24 24 are of greater height than the partitions 21, so that their upper edges are caused to project above said partitions, as seen in Fig. 4, and the upper retaining-strips 27, which are rested upon the projecting ends of the partitions 21, have notches 28, as seen in Figs. 4 and 5, in which the extremities of the upwardly-extended edge portions of plates 24 are engaged to centrally position said plates 24 within the passages 22 22 of the generating-chamber 10.

25 25 indicate terminal windings carried upon the supporting-plates 24 24, said windings being preferably of copper wire and having their turns spaced apart, as indicated in Fig. 4, and alternate windings 25 25 upon the series of plates 24 are connected in parallel with one circuit-conductor by means of a wire 26 or otherwise, while the remaining windings 25 upon the series of supporting-plates 24 and which alternate in arrangement with and intervene between the first-mentioned set of windings have similar parallel circuit connections, as seen at 26^a, with an electrical conductor of opposite polarity to that with which the first-mentioned set of windings has connection. This arrangement of alternating sets of windings in parallel connection with electrical conductors of opposite polarity is well illustrated in the dia-graphic views, Figs. 8 and 9, and it will be obvious that where a supply of electricity of sufficiently-high tension is present in the conductors with which the alternating sets of windings are connected an electrical discharge will occur between the windings of the respective sets, which discharge will be caused to take place through the intervening plates or partitions 21 and through the air-current supplied through the passages 22, in which the windings are supported, so as to generate ozone from such air. It will also be obvious that since the arrangement of the windings 25 as specified affords a comparatively great discharging-surface the capacity of the appa-

ratus for the generation of ozone is very materially increased. In the apparatus shown in Figs. 3 and 4, supposing the portions of plates 24 whereon the windings are carried to have the dimensions of five by eight inches, it will be seen that a generating-surface of ten thousand running inches is thereby afforded, and at the same time the construction is of so compact a nature as to take up but very small space.

Outside the casing 2 the discharge-pipe 12 is extended, as seen at 40, being preferably formed from non-conductive and non-corrosive substance, and adjacent to the casing 2 said pipe or conduit is provided with a regulating cock or valve 41, by means of which the rate of discharge of the ozonized air from the generating-chamber 10 may be controlled at the will of the operator. The opposite end of pipe or conduit 40 has connection with a coupling 42, from which extend opposite connections 44 44 to screw-couplings 45 45 at opposite sides of the central coupling 42. The coupling 42 is supported upon a stem or upright 43, erected upon the table 1 of the supporting-base of the apparatus.

The lateral couplings 45 45 at opposite sides of the central coupling 42 are adapted for screw connection in a well-known way with wash-bottles 46, which are thereby detachably held in position and which may contain a suitable liquid for washing the ozonized air for removal of impurities therefrom or may, if desired, contain a medicament of any description which it may be desirable to exhibit with the ozonized air. In this latter case vaporizing or atomizing nozzles may, if desired, be employed in the wash-bottles 46.

The couplings 45 for the wash-bottles 46 have connection with pipes 47, which are extended toward opposite sides of the table 1 and have at their outer ends connection with couplings 49, secured upon the table 1, valves 48 being provided for regulating the flow of the fluid through said pipes 47. The couplings 49 have nipples 50, with which are connected flexible tubes 51, the opposite ends of which have connection with other nipples 53 upon discharge-tubes 52, the body portions of which are formed from non-corrosive substance and which have, at their supported ends, forked metal end pieces 54, between which is embraced a lug 55, erected upon a pivot-pin 57, held to turn or swivel in the upper end of the corresponding outer coupling 49, as clearly shown in Fig. 7, a pivot-pin being passed through the forks 54 and lug 55 in such a way that the discharge-tubes 52 are thereby permitted to be swung in various directions to accommodate various positions of the patient to be treated. Each tube 52 has at its free end a mouthpiece 58 for convenient inhalation by the patient of the ozonized air supplied by the tube 52.

In the construction illustrated in the draw-

ings there are two of the administering-tubes 52 and mouthpieces 58; but it is evident that this number is in no way essential to my invention, since a greater number may, if desired, be employed, or in some cases a single tube and mouthpiece may be provided. Where more than one such tube and mouthpiece is employed, the valves 48 are very desirable for permitting control of the supply of ozonized air to suit the special requirements of each patient.

It will be understood that my improved generating apparatus may be employed in connection with any suitable source of electrical supply, and I do not desire to limit myself in this respect. In Figs. 6 and 8 I have illustrated the employment of the apparatus in connection with a static machine of any desired type, 63 63 representing the prime conductors of the machine, which have connection, as seen at 62 62, with condensers in the form of Leyden jars 60 60, the discharge-rods 61 61 of which may be approached or separated to regulate the intensity of the supply to the alternating sets of windings 25 in the generating-chamber of the apparatus.

In Fig. 9 I have illustrated the application of my improved generating apparatus for use in connection with a source of alternating-current supply. In this view 66 indicates an alternator which may be specially installed or may be at a power - station, and 65 indicates the circuit connections thereof which are connected with the primary of a transformer 64, the secondary of which has connection with the alternating sets of windings 25 in the generating - chamber. With this form of supply the motor 16 for driving the blower 15 may be in circuit with the generator 66, although it is immaterial whether said blower be driven electrically or otherwise.

In case the source of supply be a direct current it will be evident that a converter of any desired kind should also be in circuit with the apparatus.

From the above description it will be evident that the improved generating apparatus constructed according to my invention is of an extremely simple and inexpensive nature and is very desirable for use by reason of the increased efficiency afforded by my improvements for the generation of ozone and also by reason of the greater convenience for use afforded by the improved construction and arrangement of the parts, and it will also be obvious from the above description that the device is capable of some modification without material departure from the principles and spirit of the invention, and for this reason I do not desire to be understood as limiting myself to the precise form and arrangement of the several parts of the device herein set forth or to any special arrangement of the means of supply either of electrical energy or of air.

Having thus described my invention, what I claim, and desire to secure by Letters Patent, is—

1. An apparatus of the character described having a generating-chamber, two sets of circuit-terminal windings in said chamber, the terminal windings of one set alternating with those of the other and a source of electrical supply comprising conductors each of which has parallel connections with the circuit-terminal windings of one set within the generating-chamber.
2. An apparatus of the character described having a generating-chamber, two sets of circuit-terminal windings in said chamber, the terminal windings of one set alternating with those of the other, a source of electrical supply comprising conductors each of which has parallel connections with the circuit-terminal windings of opposite polarity.
3. An apparatus of the character described having a generating-chamber, means for admitting and withdrawing air to and from the chamber, two flattened wire coils within said generating-chamber, a glass plate extended in the chamber between said wire coils and a source of electrical supply comprising conductors of opposite polarity and connected, respectively, with the respective flattened wire coils in said chamber.
4. An apparatus of the character described having a generating-chamber, means for admitting and withdrawing air to and from the chamber, two wire coils within the generating-chamber and spaced apart, means for supporting said wire coils, a glass plate extended in the chamber between said wire coils and a source of electrical supply comprising conductors of opposite polarity and connected, respectively, with the respective wire coils in the generating-chamber.
5. An apparatus of the character described having a generating-chamber, means for admitting and withdrawing air to and from the chamber, glass partitions extended in said chamber and spaced apart, whereby passages are produced between them for the flow of air admitted to and withdrawn from the chamber, circuit-terminal windings arranged in the passages and a source of electrical supply comprising conductors of opposite polarity connected, respectively, with the respective circuit-terminal windings in said passages of the generating-chamber.
6. An apparatus of the character described having a generating-chamber, means for admitting and withdrawing air to and from the chamber, glass partitions extended in said chamber and spaced apart, whereby passages are produced between them for the flow of air, a source of electrical supply comprising conductors of opposite polarity and two sets of circuit-terminal windings connected, re-

spectively, in parallel with the respective conductors and alternately arranged in the passages between said partitions in the generating-chamber.

7. An apparatus of the character described having a generating-chamber, means for admitting and withdrawing air to and from the chamber, glass partitions extended in the chamber and spaced apart to produce between them passages adapted for the flow of air, a source of electrical supply comprising conductors of opposite polarity, plates of insulating material extended in the passages between the partitions of the generating-chamber and wire coils extended upon said plates of insulating material and connected, respectively, with the respective conductors of said source of supply.

8. An apparatus of the character described comprising a casing having a chamber the end walls of which have parallel grooves, glass plates extended lengthwise in said chamber with end edges engaged in said grooves, means for admitting and withdrawing air to and from said chamber, a source of electrical supply comprising conductors of opposite polarity and terminal windings arranged in the generating-chamber between said glass plates and connected, respectively, with the respective opposite conductors of said source of supply.

9. An apparatus of the character described comprising a casing having a chamber the end walls of which have parallel grooves, supply and discharge pipes connected with said end walls for the supply and discharge of air to and from said chamber, glass partitions the end edges of which are held in said grooves, said partitions being extended lengthwise in said chamber and being spaced apart to produce passages between them, and the end edges of said partitions being cut out to afford communications between said passages at the ends of the chamber, a source of electrical supply comprising conductors of opposite polarity and terminal windings arranged in the passages of the generating-chamber between said partitions and connected, respectively, with the respective opposite conductors of said source of supply.

10. An apparatus of the character described comprising a casing having a chamber, means for supplying and withdrawing air to and from the chamber, glass partitions extended in the chamber parallel with each other but spaced apart to produce passages for the flow of air, other glass plates arranged in the passages between said partitions, terminal windings carried on said last-named glass plates and a source of electrical supply comprising conductors of opposite polarity each of which has connection with alternate windings in the generating-chamber.

11. An apparatus of the character described comprising a casing having a cham-

ber, means for supplying and discharging air to and from said chamber, glass partitions extended lengthwise of the chamber parallel with each other but spaced apart to produce 5 passages for the flow of air, shorter glass plates in the passages between said partitions, strips extended transversely of the generating-chamber and having means of engagement with the upper and lower edges of 10 said shorter glass plates for retaining them in position, terminal windings carried on the shorter glass plates and a source of electrical supply comprising conductors of opposite polarity each of which has connection with 15 alternate windings in the generating-chamber.

12. An apparatus of the character described comprising a casing having a generating-chamber, a glass plate extended therein, 20 a source of electrical supply comprising conductors of opposite polarity and terminal windings connected therewith and arranged in the generating-chamber at opposite sides of said glass plate, means for withdrawing air 25 from the casing, and means for supplying air to the generating-chamber and comprising an air pipe or conduit and an air-forcing means connected therewith.

13. An apparatus of the character described comprising a casing having a generat- 30

ing-chamber, a glass plate extended therein, a source of electrical supply having conductors of opposite polarity and terminal windings connected therewith and arranged in the generating-chamber at opposite sides of said 35 glass plate, means for supplying air to the generating-chamber and comprising an air pipe or conduit and an air-forcing device connected therewith, means for withdrawing air from the casing and means for controlling the 40 operation of said air-forcing device.

14. An apparatus of the character described comprising a casing having a generating-chamber, a glass plate extended therein, a source of electrical supply having conductors of opposite polarity and terminal windings connected therewith and arranged in the generating-chamber at opposite sides of said 45 glass plate, means for supplying air to the generating-chamber and means for withdrawing air from said chamber and comprising an air-conduit having a controlling-valve.

In testimony whereof I have hereunto signed my name at Chicago, Illinois, this 7th day of June, 1905.

CHARLES F. BIRTMAN.

In presence of—

HORATIO H. HARWOOD,
A. B. SLATER.
